UNITED STATES PATENT OFFICE.

FRANCIS A. BRAXTAN, OF CHICAGO, ILLINOIS.

SAMPLE HOLDER.

Application filed May 31, 1923. Serial No. 642,460.

To all whom it may concern:

Be it known that I, FRANCIS A. BRAXTAN, a citizen of the United States, and a resident of Chicago, Cook County, Illinois, have 5 invented certain new and useful Improvements in Sample Holders, of which the following is a specification.

The present improvements relate to devices for holding specimens or samples of 10 fabrics, such as silk, cotton, woolen goods, etc., usually put up for sale in rolls commonly called bolts. Its principal objects are to provide means for holding such samples for ready accessibility in instances in 15 which the prospective customer desires a sample to take along, and to effect important savings of cost, both in material and salesmen's time, to the proprietor of the store where such goods are sold.

20 The most common practice, when a prospective customer asks for a sample of such goods, is for the salesman to cut off a small strip at the end of the piece, which strip may be from an inch to two inches wide 25 and up to five or six inches long. The next person to purchase from that bolt of goods is entitled to full yardage, so that measurement is made from the place where the sample had been cut, with the result that substantially to the extent of the width of the 30 goods the customer receives more goods than is paid for, with a consequent loss to the proprietor. The loss due to such cutting off of samples is very great.

35 It has been proposed heretofore to cut off a strip of material from the end of the piece and fold it up and deposit it between two flat covers hinged together in the form of a flat container of hard-pressed cardboard or 40 composition board about the size of an ordinary pocket memorandum book, say four inches by six and one-half inches, and to insert this folder containing the strip of sample material within the roll or bolt of 45 goods, preferably adjacent to the central board on which the material is wound. So far as I know that simple form of device and method for preserving samples for reference and use is the only one heretofore suggested. Various difficulties obtain with 50 respect to such a device, among which are that the salesman most frequently does not take the trouble to fold the sample carefully enough to preserve it in good condition; 55 secondly the sample is loosely positioned between the two cover leaves and is constantly

falling out during the handling, and the remnant often becomes displaced after a part thereof is cut off as a sample. A third objection is that the folder must be withdrawn each time a sample is desired. A fourth objection is that these thin and flat book-like containers, consisting merely of two thin and hard cardboard sheets face to face and hinged with a strip of adhesive 60 tape at the end, readily disappear within the body of the bolt of goods, whereupon a new sample is cut off and put in another container, and that one inserted, and so on, it frequently happening that, when the bolt 65 is entirely used up, as many as a half a dozen of these small sample books are found to have been inserted. The small container mentioned has not proven satisfactory but 70 has been extensively used.

75 Among the objects of the present improvements are to provide a device according to which such and other objections to prior practices are overcome.

80 In the accompanying drawings, which form a part of this specification, Figure 1 is a medial longitudinal section through my improved device and also through a fragment of a bolt of goods in connection with which the device is shown in its normal position for use; Fig. 2 is what may be termed the top or upper face view of the device, partly broken away; Fig. 3 is a perspective, with one of the cover members broken, showing how the specimen or sample is normally 85 folded for use; and Fig. 4 is a fragmentary longitudinal section on the line 4-4 of Fig. 2.

90 My improved device comprises first two sides or cover members 10 and 11 which are 95 preferably relatively long and narrow, say about four and one-half inches wide and twelve inches long, but the dimensions may vary within wide limits. I prefer hard-pressed cardboard or thin composition board 100 for these members. They are made unusually long so that a long sample may be folded back and forth between them without undue bunching of the material. These two cover members are hinged together at corresponding ends thereof, as by an outer piece of binding cloth 12 and an inner piece of binding cloth 13, thus making a book-like structure, the sides of which may readily 105 swing apart.

110 A metallic plate 14 is secured, as by a pair of integral clips 15, to one of the side mem-

bers as 10, this plate 14 having a slot-like opening 16 parallel with the hinge of the device, and the material of the sheet or cover member 10 is correspondingly slotted at 17 so that the slots 16 and 17 register with each other and form an opening through which a sample as 20 may extend. The metallic plate 14 carries a stop 18 which is shown in the form of a hook or spring clip adapted to engage the board 19 upon which the material 21 is wound. This stop 18 limits the movement of the device into the bolt and overcomes one of the objections mentioned. When formed as a spring clip it also acts to retain the device against displacement when the bolt is carried or thrown about, and it also assists in holding the structure when the sample is being withdrawn. The cover member 11 has an opening 30 accommodating the stop 18 in the relative movements of the cover members.

To facilitate the withdrawal of the sample and to provide against its bunching at the opening 16-17 I preferably add a guide member which is shown in the form of a bail 23 having a roller crosspiece 24, this roller being shown as a tube held by the turned-inward ends of the side arms of the bail. The bail is pivoted for swinging movements by means of two pieces of tape 25, 25, as well shown in Figs. 3 and 4.

In practice when a new piece of goods comes upon the floor the first step is to cut off from the end thereof a strip of material 35 the full width of the piece to be used as a sample from time to time. This sample strip is applied to the present device by first opening the leaves or cover members 10 and 11 substantially as shown in Fig. 3, moving 40 the bail 23 out of the position shown, as by swinging it against the cover member 11, thus leaving the inner surface of the cover member 10 free. The next step is to thread the end of the sample 20 through the opening 16-17 and thereupon lay the first stretch of the sample straight out lengthwise upon the member 10. The next step is to swing the bail 23 back into the position shown in Fig. 3, the roller 24 thereupon lying on top 45 of a section of the sample. The sample is next folded back and forth, the first fold being adjacent to the roller 24, as well illustrated, and this folding back and forth continues until the specimen is laid out in that 50 manner, one fold upon another, but leaving its inner free end projecting slightly beyond or at least being about flush with the inner or open end of the device. The cover member 11 is then laid over or superposed upon 55 the cover member 10 and the sample is thus covered by the device, which constitutes a substantially flat container for it.

It will be noted from Figs. 2 and 3 that on one of the cover members, as 11, I provide a strip 27 of what may be considered

sandpaper or as having been formed by drawing a brush with glue across the device there and then sprinkling sand upon it, which element 27 constitutes means for holding the free end of the sample releasably. When the cover members are folded together and the device is positioned as shown in Fig. 1 the pressure of the goods forces this rough or abrasive surface 27 into such contact with the sample as to hold the inner end thereof against movement until direct pulling strains are had upon it, such direct pulling strains being sufficient to cause the sample to slip and come away from the holding surface 27.

Having thus folded the strip within the container the device is inserted adjacent to the board 19 as shown in Fig. 1, with the outer end of the sample 20 projecting beyond the material of the bolt and thus being available for pulling strains upon it. Now when the prospective customer desires a sample it is only necessary for the salesman to withdraw a few inches of the sample and cut it off, without removing the device, and to continue doing so from time to time until the particular specimen is used up, when another strip is cut off of the end of the piece and similarly positioned in the container.

I contemplate as being included in this invention such modifications of and departures from what is herein specifically shown and described as fall within the scope of the appended claims.

I claim:

1. In a sample holder of the character described, the combination of a pair of substantially flat cover members hinged together at corresponding end portions thereof so as to fold one upon the other and forming a container for a strip-like sample, said container having a clip thereon adjacent to the hinge adapted to limit the movement of said container into a bolt of goods and to hold the container upon the board upon which the goods are wound, said container having an opening adjacent to the hinged end portion thereof through which such sample may be drawn, and a cross-member normally between the cover members partially around which the sample may be folded.

2. In a sample holder of the character described, the combination of a pair of substantially flat cover members hinged together at the corresponding end portions thereof so as to fold one upon the other and forming a container for a strip-like sample, said container having an opening adjacent to the hinged end portion thereof through which such sample may be drawn, and means including a swinging bail within the container for controlling the movement of such strip-like sample when drawn upon

from without the container whereby all successive portions of such strip-like sample within the container and extending from said opening to the end of the sample are 5 successively drawn in lines of movement leading to the said opening.

3. In a sample holder of the character described, the combination of a pair of substantially flat cover members hinged together 10 so as to fold one upon the other and forming a container for a strip-like sample, said container having a stop thereon adjacent to the hinge adapted to limit the movement of said container into a bolt of goods,

said container having an opening adjacent 15 to the hinged end portion thereof through which such sample may be drawn, and a swinging bail between the cover members and hinged near the hinge of the cover members, said bail having a cross piece partially around which such sample may be folded, to guide such strip in its movement toward said opening when drawn upon from without the container, and means for releasably holding the end of such strip 20 while intermediate portions thereof are being withdrawn from the container.

FRANCIS A. BRAXTAN.
